DISPLAY RACK FOR FABRIC SAMPLES AND THE LIKE

George H. Jantzen, New York, N.Y., assignor to Steinhalt
Sample Co., Inc., New York, N.Y., a corporation of
New York

Filed Jan. 8, 1962, Ser. No. 68,229

Term of patent 14 years

(Cl. D80—9)

FIG. 1 is a perspective view of a display rack for fabric samples and the like showing my new design;

FIG. 2 is a front elevational view thereof; and

FIG. 3 is a side elevational view thereof.

The broken line representations of the fabric samples or swatches are for the purposes of illustration only.

I claim:

The ornamental design for a display rack for fabric samples and the like, substantially as shown and described.
